(57) **CLAIM**

The ornamental design for a display screen with graphical user interface, as shown and described.

DESCRIPTION

FIG. 1 is a front view of a display screen with graphical user interface according to a first embodiment of the claimed design.

FIG. 2 is a rear view of the display screen with graphical user interface of FIG. 1.

FIG. 3 is a top view of the display screen with graphical user interface of FIG. 1.

FIG. 4 is a bottom view of the display screen with graphical user interface of FIG. 1.

FIG. 5 is a left side view of the display screen with graphical user interface of FIG. 1.

FIG. 6 is a right side view of the display screen with graphical user interface of FIG. 1; and,

FIG. 7 is a front view of a display screen with graphical user interface according to a second embodiment of the claimed design.

The dash-dot-dash broken lines showing the display screen and the dash-dot broken lines showing the graphical user interface illustrate portions of the display screen with graphical user interface that form no part of the claimed design.

The rear view, top view, bottom view, left side view, and right side view of the display screen with graphical user interface of FIG. 7 is the same as shown by FIGS. 2, 3, 4, 5, and 6, respectively.

The lighter density oblique hatch shading, heavier density oblique hatch shading, and cross-hatch shading in FIG. 7 represent contrast in appearance, although no particular color is claimed. Any pattern formed by the lighter density oblique hatch shading, heavier density oblique hatch shading, and cross-hatch shading forms no part of the claimed design.
